UNITED STATES PATENT OFFICE.

HERBERT M. FRIENDLY, OF CHICAGO, ILLINOIS.

AUTOMATIC TELEPHONE SYSTEM.

Application filed October 27, 1920, Serial No. 420,017. Renewed June 10, 1925.

The present invention has for its broad objects, the improvement of automatic and semi-automatic telephone systems, looking toward lowering maintenance costs and the 5 affording of novel operative conveniences to users.

The invention in the specific form chosen for its illustration herein, contemplates a so-called two-wire common battery automatic 10 telephone system as has been widely used, the present invention necessitating novel departures from equipments heretofore known, so far as I am aware, in attaining the novel objects, while retaining certain operative 15 functions which are known.

In overcoming limitations of present selector switches and co-operating or auxiliary equipment elements as used in automatic telephone systems, the present invention contemplates the following novel objects:—

a. Means, whereby in the event an open private conductor of a trunk or link leading to the succeeding switching element (leading directly or leading indirectly through a repeater device) the selector (first selector, or succeeding selector) seizing the said trunk terminals, the seizing selector will be incapacitated against automatically releasing consequent to the calling party hanging up 30 the telephone receiver to terminate the service, or perhaps initiate a new call by again removing it thereafter. The selector will remain off-normal indicating an abnormal condition and must be restored by the exchange attendant.

b. Means, whereby when a selector is in engagement with a trunk and the calling party has disconnected from the service and the selector is incapacitated against automatic restoration as set forth in the foregoing paragraph, "a", the line or trunk leading to the selector is guarded against seizure, by its private being grounded, until the selector is restored by the exchange attendant.

c. Means, whereby when a selector functions as set forth in the foregoing paragraphs "a" and "b", the line or trunk engaged by it is guarded against seizure by its private conductor becoming grounded until the selector is restored by the exchange attendant.

d. Means, whereby when a selector functions as set forth in the foregoing paragraphs "a", "b" and "c", a lamp will glow (or other signal device display) indicative

that a selector has been incapacitated as set forth in the foregoing paragraphs.

e. Means, whereby when a selector functions as set forth in the foregoing paragraphs "a", "b" and "c", a lamp will glow (or other signal device display) indicative that a selector has stepped off-normal, and then extinguish, indicative that the selector has seized a trunk in normal condition.

f. Means, whereby when a selector functions as set forth in paragraphs "a", "b" and "c", a continuous tone will be projected towards the calling telephone, indicative that the call-selecting cannot progress, due to an inoperative link having been encountered. This application of a tone audible to the calling party applies only where the calling line remains connected to the selector as when no pre-selector is employed.

g. Means, whereby when a selector has normally functioned and operatively seized a selected trunk link leading to a successive equipment element, a distinctive tone, audible to the calling party will be applied to the leading-in line conductors indicative thereof.

h. Means, whereby when a selector fails to function normally and select and seize a disengaged trunk after its primary vertical operation, the specific selector will become incapacitated against releasing and will otherwise function as if an open trunk had been seized projecting a tone indicative of the condition towards the calling telephone; further, indicative that the call-selecting cannot progress due to an inoperative link having been encountered. The reference to the application of a tone herein applies only when no pre-selector is employed.

i. It is a further object of the present invention to afford a trunk repeater, used primarily for translating from "three-wire" to "two-wire" operation (and perhaps also the further object of localizing the battery supply to the calling party where the called telephone is in a remote exchange district), so if a selector, (first or succeeding) of the present invention seizes it in gaining access to the trunk leading therefrom, the selector will adapt itself to the condition of the trunk leading from the remote side of the repeater. That is to say, though the line conductors and a private conductor lead from the selector bank contact set seized, and they extend to the incoming side of the repeater and that

two line conductors only lead from the outgoing side of the repeater, terminating in a

selector or a connector (or other equipment element) at a distant exchange. The selector seizing the trunk through the repeater will function (as set forth in the foregoing paragraphs "a" to "h" inclusive), as if the intervening repeater were not present and the three-wire trunk were continued direct to the equipment element at the remote end of the trunk.

10 The foregoing, and other novel objects of the present invention, and the invention itself will be understood from the following description thereof, together with the accompanying drawings in which:—

15 Fig. 1 shows a calling telephone leading to a preselector at the exchange, the preselector being in access to a first selector of my invention.

Fig. 2 which is joinable on the right of Fig. 1, so the lines extending towards the margins register, is a selector of my invention modified somewhat from the one shown in Fig. 1.

20 Fig. 3 is a holding circuit adapted to be introduced between Figs. 2 and 5 (in lieu of Fig. 4) so the lines extending towards the margins register. It may also be similarly introduced between Figs. 1 and 2.

Fig. 4 is a trunk repeater of my invention 25 adapted to be introduced between Figs. 2 and 5 so the lines extending towards the margins register. It may also be similarly introduced between Figs. 1 and 2.

Fig. 5 is a well known form of connector 30 belonging to the general class as shown in U. S. Patent No. 13,901 reissued April 13, 1915 to Frank Newforth. A feature of the referred-to connector of Newforth and the connector shown in Fig. 5 is its function 35 which causes the current supplied over the calling line to be reversed in direction incident to the called party responding. It is shown herein for the purpose of elucidating the operation of Figs. 1 to 4 inclusive. It 40 is adapted to attach to the right of either Figs. 1, 2, 3, or 4 so the lines running toward the margins register.

Figs. 6 to 11, inclusive, show how the various figures are to be assembled (the lines 45 extending to adjacent margins registering), to display the various alternative equipment relationships as may occur in a comprehensive exchange system contemplated under the invention.

50 Heretofore in automatic telephone exchange operation a serious traffic phase has been the large number of complaints of failure to gain a response, when subsequent tests by exchange attendants would fail to discern a faulty condition of the calling line 55 or the called line, the inference therefore being that the failure was due to a faulty condition of a link or common switching element. Aside from the purely service aspects this condition increases maintenance

costs without commensurate results; in fact the large number of complaints untraceable to faulty conditions, retards the work of tracing actual faults and creates an element of doubt in all complaints, which condition 70 operates psychologically against diligent search by the exchange attendants. While in certain exchanges more or less complete tests are made of all trunks and apparatus elements periodically (usually at night when 75 the traffic is light), such extensive routine testing of many trunks and apparatus elements in search for a few possible defective elements is costly, the costs of which will carry a substantial increased equipment cost, 80 provided the necessity for routine testing can be obviated or if complaints can be reduced thereby. This is from the purely operating aspect, aside from the traffic phase as concerns 85 the users directly. Even under conditions of rigid, periodic routine testing the possibility occurs of defective equipment links remaining in service a considerable time, vitiating many calls before the defective elements are discovered in the routine 90 testing, or discovered in the process of their defective switching operation, by the exchange attendants.

Another objectional feature or limitation heretofore existing in exchanges of the class 95 referred to is that should a defective selector or an open trunk, or open private companion thereto, be encountered in call-selecting the call is vitiated. Further, the calling party has no means of knowing the condition 100 ensuing, and, because of not gaining the response of the called party, is led to assume his (the calling) telephone or the called telephone line is out of order. Even though the difficulty may be attributed to central 105 office switching equipment, the calling party is frequently powerless to switch through because of encountering the same defective trunk in successive attempts.

The present invention has for its salient, 110 general object the elimination of the necessity for persistent routine testing by reason of providing functions in the links which will incapacitate the link or element thereof for subsequent use after it has become seized, 115 provided it fails to complete the call normally, by reason of its defectiveness, or the defectiveness of a co-operating link. The exchange attendant can forthwith re-instate the element in service, or at least provide against 120 its subsequent seizure until its defectiveness has been corrected. Thus, after a call has been vitiated due to a defective link, an object of the present invention is to guard subsequent calls against a similar fate because of 125 the link. It also evidences the condition to the exchange attendants.

Referring to the drawings:—

The calling automatic telephone set P leads over line conductors 2 and 3 to pre- 130

selector K located at the exchange. The pre-selector K is in access to a plurality of first selectors, one only, as shown in schematic detail in Fig. 1, is reached over line conductors 4 and 5 and private conductor 6. The first selector is in access over common trunks to a plurality of second selectors, one only of which is shown, over line conductors 7 and 8 and private conductor 9. The second selector is shown in schematic detail as Fig. 2, and is in access to a plurality of common trunk equipments, one only of which is shown in schematic detail in Fig. 3, reached over line conductors 204 and 205 and private conductor 206. The trunk leading from Fig. 3 over conductors 301 and 304 terminates in the connector shown in schematic detail in Fig. 5 reached over conductors 512 and 513. The repeater Fig. 4 may be substituted for Fig. 3 as will be discussed presently. The called telephone Q is reached by the connector Fig. 5, over conductors 501 and 502.

The calling automatic telephone P is the usual service type having a sending device 17 of the general class, as shown in British Patent to Dicker, No. 29,654 of 1910. The pre-selector K is of the general class, as shown in U. S. Patent to Lamb No. 1,193,160, granted August 1, 1916. The selectors Figs. 1 and 2 are of the general class as shown in U. S. Patent to Keith & Erickson No. 815,321, granted March 13, 1906, of course modified in such mechanical and circuit details so as to operate on the so-called two-wire principle, and further as contemplated in the present invention. The connector Fig. 5 is of the general class as shown in U. S. Patent to Keith & Erickson No. 815,176, granted March 13, 1906, of course modified in such mechanical and circuit details as to operate on the so-called two-wire principle, the said connector being well known in the art. The telephone Q is similar to P and is shown as a called telephone on bank contact set twenty-two reached, as stated, over line conductors 501 and 502. Conductor 503 leads to the cut-off relay 504 of a pre-selector similar to K, so when the set Q is called by the connector wipers 505 and 506 seizing the bank contacts 507 and 508 leading to line conductors 501 and 502 respectively and private wiper 509 seizes and grounds bank contact 510 leading over conductor 503 to the winding of cut-off relay 504 the operative windings of the pre-selector on the called line will be disconnected. The conductors 501, 502 and 503 are common to other bank contacts before connectors, reachable by the same co-ordinate operation of the conductor wipers. The foregoing line bank contact arrangement and line cut-off relay arrangement relating to the called line is not new, the present invention being primarily directed to im-

provements in the selectors, repeater and the alternative holding circuit; of course, contemplating use with connecting switches also.

In practice it is usual to employ a single battery source, and this battery has one of its poles permanently grounded. Also it is usual to employ a single ground, the said battery and ground being multiplied respectively to terminals of the elements adapted to each respectively. To simplify the drawings and descriptions the battery and ground is shown as independent sources throughout, wherever applied. In the descriptions, when a circuit is traced to a winding, the opposite terminal of which is shown applied to grounded battery or to ground, the described circuit is to be considered traced to ground through the winding or direct to ground as indicated.

Also, when a circuit is traced "to the winding" of a relay, resistance, or magnet, it is to be understood as traced to "the free winding terminal" thereof, and through the winding and beyond as indicated.

Tone sources are indicated, designated "cut-in tone" and "busy tone" respectively. The said respective tone sources are represented conventionally as an inductorium, the primary winding of which, has one terminal applied to grounded battery and the other terminal thereof applied to ground through an interrupter device adjustable to the desired period. The secondary winding will apply induced potential from ground to the receiving conductor leading to the switches shown and to other switches in common therewith. The tones are thus indicated as "ground seeking" and the receiving conductors from the respective tone sources will be referred to as if they constituted a tone source in themselves.

To aid in locating designated elements referred to by number, in all but Fig. 1, the first digit will correspond numerically with the figure number.

In elucidation of the present invention the performance of the equipments will be detailed under different assumed operative conditions.

Assume a call from telephone P to telephone Q in which Figs. 1, 2, 3 and 5 are included. Upon the receiver being removed from the hookswitch to initiate the call, pre-selector K will seize the trunk leading to the first selector. Talking and receiver-exciting battery will be supplied to telephone P over the following traced circuit:—Upper winding of relay A, conductor 10, resting contact 11, armature 12, conductor 5, wiper 13 of pre-selector K, conductor 3, telephone P, conductor 2, wiper 14 of pre-selector K, conductor 4, armature 15, resting contact 16, conductor 17 to the winding of relay A. Relay A will actuate, applying ground on

its armature 18 to its working contact 19 and over conductor 20, to the winding of slow-releasing relay B, causing said B to actuate. Grounded contact 21 is engaged by armature 22, the said ground being applied over conductor 23 to conductor 6. Ground on the latter conductor serves to disassociate the attachments to the line conductors in the pre-selector K and also to 10 guard the first selector against seizure by any other pre-selector. The first selector is now in readiness to receive the control open impulses from the sending device 17 at telephone P.

Upon the calling party sending one open impulse, (constituting the digit "1") relay A will retract and again attract its armature one time consequent thereto, relay B sustaining over the current lapse. Ground on 20 armature 18 will be applied to resting contact 24, for the interval of retraction, and over conductors 25, armature 26, resting contact 27, conductor 28, armature 29, working contact 30, series winding of slow-releasing 25 relay C, conductor 31 to the winding of the vertical magnet (designated VERT. M.), causing the said magnet to actuate and step the shaft carrying wipers 32, 33 and 34 one vertical step into registry with the first bank 30 level. Relay C will actuate co-incident with the energization of the vertical magnet and sustain for its period after the deenergization thereof. Consequent to the shaft stepping off-normal, springs 35 and 36, 37 and 38, 39 and 40, and 41 and 42 respectively engage. A circuit can now be traced from the winding of relay E, conductor 43, conductor 44, spring 36, spring 35, conductor 45, conductor 46, working contact 47, armature 48 to grounded conductor 6. The winding of relay E is shunted by resistance 49, and, moreover, relay E is marginally adjusted to not operate in series with the inside winding of relay D, but relay D will 45 operate when its inside winding is included in series with and deriving current through the winding of relay E. Relay E will actuate under the energization of the traced circuit path.

Upon relay C deactuating its period after the shaft has been stepped up the one level and a prolonged closure of the telephone path ensues because of the restoration of the sending device 17, an energizing circuit can 50 be traced from grounded conductor 6, armature 48, resting contact 50, armature 51, working contact 52, conductor 53 to the winding of the rotary magnet (designated ROT. M.). A locking circuit is established 55 co-incident with the actuation of relay E, traced as follows:—grounded working contact 54 on relay E, armature 55, conductor 56, conductor 57, resting contact 58, armature 59 (the contact 58 and armature 59 60 being auxiliarily mounted on the rotary magnet), conductor 45, spring 35, spring 36, conductor 44, conductor 43 to the winding of relay E. Thus, when relay E actuates it will lock itself until the last described path is opened at contact 58 incident to the actuation of the rotary magnet. The latter function will occur resultant to the closure of armature 48 upon resting contact 50. The rotary magnet will therefore actuate the period of relay C after the shaft is caused 70 to step vertically and stop, causing the shaft to rotate one step, its wipers 32, 33 and 34 engaging the first set of bank contacts 60, 61 and 62 respectively, relay E unlocking 75 incident to the attraction of rotary magnet 80 armature 59 from resting contact 58.

If bank contact 62 be assumed to have a ground on same due to a "busy" condition, as shall be clear presently, the said ground communicated to wiper 34, conductor 63, working contact 64, armature 65, conductor 66, conductor 67 (inside winding of relay F being short circuited through contact 64 and armature 65), armature 68, resting contact 69, conductor 57, resting contact 58, 85 armature 59, conductor 45, spring 35, spring 36, conductor 44, conductor 43 to winding of relay E, will cause the latter to actuate and again close the described energization circuit to the winding of the rotary magnet. This will cause the shaft to be driven a step further rotarily, the relay E locking coincident with its actuation over the described path and then unlocking incident to the actuation 90 of the rotary magnet attracting its armature 59 from its resting contact 58. If the wiper 34 again encounters a grounded bank contact the same cycle of operations incident to driving the shaft an additional step from the first bank set will ensue. However, assuming that the bank contact 62 is ungrounded, then, when wiper 34 engages said 62, no ground will be communicated from said 34 over the circuit to the winding of relay E, and therefore no energizing circuit to the 95 winding of the rotary magnet will be re-established. The described path from the winding of relay E to conductor 57 and to grounded wiper 34 may be now traced through inside winding of relay D to conductor 6, causing relay D to 100 actuate. The ground assumed as applied to wiper 34 serves as a short circuit to the said inside winding on relay D.

Consequent to the actuation of relay D, 105 armature 68 will engage working contact 70, leading to conductor 71, and to grounded conductor 6. The ground from conductor 6 will be communicated over conductor 67, conductor 66, armature 65, working contact 64, conductor 63, wiper 34, to bank contact 62. Armatures 12 and 15 will engage working contacts 72 and 73, and disengage resting contacts 11 and 16 respectively. Leading-in line 110 conductors 5 and 4 are now continued over 115

conductors 5 and 4 are now continued over 120

conductors 5 and 4 are now continued over 125

conductors 5 and 4 are now continued over 130

conductors 74 and 75 to wipers 33 and 32, bank contacts 61 and 60, conductors 8 and 7, conductors 205 and 204, to armatures 212 and 215 on relay D², conductors 210 and 217 to the upper and lower windings of relay A² respectively.

Relay A will deactivate, followed by relay B its period thereafter, the latter relay thus holding a ground on conductor 6 an appreciable period after the telephone P has been extended to receive talking battery and receiver-exciting battery from relay A² in lieu of relay A. Upon relay A² actuating due to its windings becoming energized over the traced path including telephone P, its grounded armature 218 will engage working contact 219, applying ground over conductor 220 to the winding of slow-releasing relay B², causing said B² to energize and actuate. Grounded working contact 221 is engaged by armature 222 so ground is communicated to conductor 223, conductor 206, conductor 9, bank contact 62 and over the traced path to conductor 6. Bearing in mind the slow release characteristic of relay B the ground described as from working contact 221 is applied to conductor 6 before the relay B deactuates, so no ground lapse occurs with relation to conductor 6, relay D remaining actuated, deriving its energizing current through the unactuated marginal relay E.

It is to be noted here that when relay B deactuates its period after the deactuation of relay A armature 65 retracts from working contact 64, thereby removing for an instant the short-circuit from the low-resistance inside winding of relay F. Energizing current of relay D (and also the pre-selector cut-off relay) being now derived through the inside winding of relay F to the grounded working contact 221 in Fig. 2 relay F will actuate, its armature 76 engaging working contact 77. A locking circuit now exists from grounded battery, restricting resistance 78, working contact 77, armature 76, outside winding of relay F, conductor 79, spring 39 to off-normal ground on spring 40. This will insure the attraction of armature 80 from resting contact 81 and armature 82 from resting contact 83. The object of relay F will be clear presently. However, suffice it to say here, that if ground were not applied ahead so current from conductor 67 will not be derived through relay F as set forth, it, of course, would not actuate and lock. At this juncture relays D, F, A² and B² are actuated.

Upon the calling party sending one open impulse (constituting the second digit of the called number) relay A² will retract and again attract its armature one time consequent thereto, relay B² sustaining over the current lapse. Ground on armature 218 will be applied to resting contact 224 for the interval of retraction and over conductor 225,

armature 226, resting contact 227, conductor 228, armature 229, working contact 230, series winding of slow-releasing relay C², conductor 231, to the winding of the vertical magnet (designated VERT. M.), causing the said magnet to actuate and step the shaft carrying wipers 232, 233, and 234 one vertical step into registry with the first bank level. Relay C² will actuate coincident with the energization of the vertical magnet and sustain for its period after the deenergization thereof. Consequent to the shaft stepping off-normal, springs 235 and 236, 237 and 238, 239 and 240 and 241 and 242 respectively engage. A circuit can now be traced from the winding of relay E², conductor 243, conductor 244, spring 236, spring 235, conductor 245, conductor 246, working contact 247, armature 248, to grounded conductor 206. The winding of relay E² is shunted by resistance 249, and moreover, relay E² is marginally adjusted to not operate in series with the inside winding of relay D², but relay D² will operate when its inside winding is included in series with and deriving current through the winding of relay E². Relay E² will actuate under the energization of the traced circuit path.

Upon relay C² deactuating its period after the shaft has been stepped up the one level and a prolonged closure of the telephone path ensues because of the restoration of the sending device 17 an energizing circuit can be traced from grounded conductor 206, armature 248, resting contact 250, armature 251, working contact 252, conductor 253, to the winding of the rotary magnet (designated ROT. M.). A locking circuit is established co-incident with the actuation of relay E², traced as follows:—grounded working contact 254 on relay E², armature 255, conductor 256, conductor 257, resting contact 258, armature 259 (the contact 258 and armature 259 being auxiliary mounted on the rotary magnet), conductor 245, spring 235, spring 236, conductor 244, conductor 243, to winding of relay E². Thus, when relay E² actuates it will lock itself until the last described path is opened at contact 258 consequent to the actuation of the rotary magnet. The latter function will occur resultant to the closure of armature 248 upon resting contact 250. The rotary magnet will therefore actuate the period of relay C² after the shaft is caused to step vertically and stop, causing the shaft to rotate one step, its wipers 232, 233 and 234 engaging the first set of bank contacts 260, 261 and 262 respectively, relay E² unlocking incident to the attraction of rotary magnet armature 259 from the resting contact 258.

If bank contact 262 be assumed to have a ground on same due to a "busy" condition, as shall be clear presently, the said ground communicated to wiper 234, conductor 263,

working contact 264, armature 265, conductor 266, conductor 267 (inside winding of relay E^2 being short-circuited through contact 264 and armature 265), armature 268, 5 resting contact 269, conductor 257, resting contact 258, armature 259, conductor 245, spring 235, spring 236, conductor 244, conductor 243 to winding of relay E^2 , will cause the latter to actuate and again close the described 10 energization circuit to the free terminal of the winding of the rotary magnet. This will cause the shaft to be driven a step further rotarily, the relay E^2 locking co-incident with its actuation over the described 15 path and unlocking incident to the actuation of the rotary magnet attracting its armature 259 from its resting contact 258. If the wiper 234 again encounters a grounded bank contact the same cycle of operations incident 20 to driving the shaft an additional step from the first bank set will ensue. However, assuming that the bank contact 262 is ungrounded. Then, when wiper 234 engages said 262 no ground will be communicated 25 from said 234 over the circuit to the winding of relay E^2 and therefore no energizing circuit to the winding of the rotary magnet will be re-established. The described path from the winding of relay E^2 to conductor 30 257 and to grounded wiper 234 may now be traced through inside winding of relay D^2 to grounded conductor 206, causing relay D^2 to actuate. The ground assumed as applied to wiper 234 serves as a short-circuit to the 35 said inside winding on relay D^2 .

Consequent to the actuation of relay D^2 , armature 268 will engage working contact 270, leading to conductor 271, and to grounded conductor 206. The ground from conductor 206 will be communicated over conductor 267 conductor 266, armature 265, working contact 264, conductor 263, wiper 234 to bank contact 262. Armatures 212 and 215 will engage working contacts 272 and 45 273, and disengage resting contacts 211 and 216 respectively. Leading-in line conductors 205 and 204 are now continued over conductors 274 and 275 to wipers 233 and 232, bank contacts 261 and 260, conductors 50 208 and 207, conductors 302 and 301 of Fig. 3, 304 and 301 to leading-in line conductors 513 and 512 of Fig. 5 respectively. Included between conductors 302 and 304 is the series winding of slow-releasing relay 55 A^3 shunted by non-inductive resistance 305. The object of Fig. 3 will appear presently. However suffice it to say at this time that the relay A^3 and its shunt 305 are in the same exchange office as Fig. 2 and that conductors 304 and 301 lead to a remote exchange office wherein Fig. 5 is located.

The calling telephone P is now related telephonically to conductors 513 and 512 of Fig. 5. Conductor 513 extends to resting contact 515 engaged by make-before-break

spring 516, conductor 517 to upper winding of relay A^5 . Conductor 512 extends to resting contact 518 engaged by make-before-break spring 519, conductor 520 to lower winding of relay A^5 . 70

Relay A^2 will deactivate, followed by relay B^2 its period thereafter, the latter relay thus holding a ground on conductor 206 an appreciable period after the telephone P has been extended to receive talking battery and receiver-exciting battery from relay A^5 in lieu of relay A^2 . Upon relay A^5 actuating due to its windings becoming energized over the traced path including telephone P, its grounded armature 521 will engage working contact 522 applying ground over conductor 523 to the winding of slow-releasing relay B^5 , causing said B^5 to energize and actuate. Grounded armature 524 engages working contact 525 and applies ground to conductor 526 and to conductor 514. 80 85

The subsequent functioning of the vertical magnet (designated VERT. M.) and the rotary magnet (designated ROT. M.) responsive to the calling party sending the third series of two open impulses and the fourth series of two open impulses constituting the third and fourth digits respectively, of the called telephone number, wherein wipers 505, 506 and 509 are caused 90 to engage bank contacts 507, 508, and 510 respectively, and the called telephone Q signaled, will not be detailed since the connector Fig. 5, as set forth at the outset is well known in the art, and that therefore the 95 present invention is not specifically directed to its functions beyond what have been detailed in relation to the application of ground to conductor 514, and the reversing of projected battery from the windings of relay A^5 as will be explained presently. 100 105

When the described energizing circuit including relay A^5 is established the winding of relay A^3 is included in series with same, and it will actuate, and, due to its slow-releasing characteristic will sustain over all controlling impulses sent from sending device 17 in telephone P. Thus, grounded armature 306 will engage working contact 307 and ground conductor 303, and maintain the said 303 grounded until a prolonged opening of the described energizing path as would be caused by the receiver of the calling telephone being placed upon the hookswitch for a brief period; five seconds, for example. 110 115 120

Bearing in mind the slow-release characteristic of relay B^2 , the ground described as from armature 306 is applied to conductor 209 and over the traced path to conductor 206, before the relay B^2 deactuates, so no ground lapse occurs with relation to conductors 206 or 6, relays D and D^2 remaining actuated, D deriving energizing current as described and D^2 deriving its energizing 125 130

current through the unactuated marginal relay E², the holding ground for both said D and D² being derived from armature 306.

- It is to be noted here that when relay B² deactuates, its period after the deactuation of relay A² armature 265 retracts from working contact 264, thereby removing for a brief period the short-circuit from the low-resistance inside winding of relay F². Energizing current of relay D (and also the pre-selector cut-off relay) being now derived through the inside winding of relay F² to the grounded armature 306 in Fig. 3, relay F² will actuate, its armature 276 engaging working contact 277. A locking circuit now exists from grounded battery, restricting resistance 278, working contact 277, armature 276 outside winding of relay F², conductor 279, spring 239 to off-normal ground on spring 240. This will insure the attraction of armature 280 from resting contact 281 and armature 282 from resting contact 283. The object of relay F² will be clear presently. However, suffice it to say here, that if ground were not applied ahead so current from conductor 267 will not be derived through it, it, of course, would not actuate and lock. At this juncture relays D, F, D², F², A³, A⁵ and B⁵ are actuated.
- The foregoing descriptions contemplated a normal call selecting function. That is, that the equipment and linkable circuit path between the calling telephone P and the called telephone Q is normal and idle.
- It will now be assumed, first, that when wipers 32, 33 and 34 seized bank contacts 60, 61 and 62 trunk conductor 7 leading to second selector Fig. 2 is open at some point between bank contact 60 and the ground permanently applied to the lower winding of relay A². In such event neither relay A² nor its dependent relay B² will actuate and ground conductor 206 as set forth. Relay D will actuate normally when the bank contacts 60, 61 and 62 are seized, disassociating relay A. Relay A followed by its dependent relay B will now deactuate. Then, when relay B deactuates, there having been no supplemental ground applied from conductor 206, no current will be derived through the inside winding of relay F in maintaining relay D and therefore relay F will not actuate and lock as described. Relay F remaining normal, when relay A deactuates incident to relay D actuating (relay E deactuating consequent to the wipers attaining the first rotary position), a locking circuit for relay D can be traced from grounded armature 18, resting contact 24, conductor 25, armature 26, working contact 84, outside winding of relay D, conductor 85, armature 82, resting contact 83, conductor 86, off-normal spring 41, spring 42, restricting resistance 87 to grounded battery. Armature 22 of relay B retracts from grounded working contact 21 a suffi-

cient period before armature 88 engages resting contact 89 consequent to the deactuation to create a lapse of ground on conductor 6 of sufficient period to allow the cut-off relay in the pre-selector K to restore before the path from grounded off-normal spring 40, spring 39, conductor 79, armature 80, resting contact 81, armature 88, resting contact 89, conductor 23 to conductor 6 is established. The latter regrounding of conductor 6 guards the selector in Fig. 1 against seizure by a pre-selector (perhaps K in a newly initiated call from telephone P), and due to relay D being locked actuated the ground on conductor 6, attached conductor 71 applied to working contact 70, armature 68, conductor 67, conductor 66, armature 65, resting contact 90, conductor 63, wiper 34 will be applied to engaged bank contact 62. Thus, bank contact 62 (and its multiples) is guarded against seizure as long as the wiper 34 is in engagement, and thus prevents a second call being vitiated due to encountering the open trunk. It is clear, now, that not only is the selector which encountered the defective trunk guarded against seizure but the trunk seized is so guarded, and, further, this guarded condition will exist until the selector is released manually by the office attendant, for the traced circuit including the release magnet will be open due to armature 26 being attracted from resting contact 27, relay D being locked actuated.

Referring again to relay B, armature 65 and its resting contact 90 is so adjusted that when said 65 retracts from working contact 64 a lapse of short-circuit around the inside winding of relay F will occur of sufficient duration to cause the relay F to attract its armature 76 against its working contact 77, provided, of course, that wiper 34 receives ground from bank contact 62 following the seizure thereof. The inside winding of relay F must be short circuited at all times, except at the instant the armature 65 is retracting, otherwise, if a selector wiper corresponding to 34 engages a bank contact multiplied with the guarded bank contact 62 the battery potential carried on the private wiper of a normal selector while hunting will traverse the inside winding of relay F in reaching conductor 6 over the path traced, causing said F to actuate and thereby upset the guarded condition of its selector, leading-in, as well as its selector engaged private bank contact. This is assuming the selector has become primarily incapacitated due to the wiper 34 failing to receive ground. The armature 65 may be a double one to promote ease of adjustment (allowing one to retract, followed by the other, for example) to provide for the short-circuit lapse.

In a normal connection, wherein relay F actuates and locks for the duration of the service, when its locking circuit is opened

consequent to the shaft restoring and off-normal springs 39 and 40 disengaging, relay D is not locked through its outside winding and is therefore held actuated (until springs 39 and 40 disengage) by the energization of its inside winding in series with winding of relay E as described hereinbefore.

In view of the fact relay F in any event is short-circuited for a period after relay D 10 energizes (and relay A deactuates resultant thereto) and closes its armature 26 into engagement with working contact 84, the traced locking path including the outside winding of relay D will become closed and 15 will therefore aid in attracting the armatures of said D. Then, if relay F actuates because of a normal seizure and the said locking path is opened the inside energized winding will support the said relay D actuated. 20 A normal release (as by calling party replacing receiver on the hookswitch) before the wipers have seized a bank contact and therefore under the condition of relay D being normal and relays A and B restoring 25 to normal will occur over the following energized path causing the release magnet (designated RLSE. M.) to actuate to unlock the shaft for restoration; grounded armature 18, resting contact 24, conductor 25, armature 26, resting contact 27, conductor 28, 30 armature 29, resting contact 91, spring 37, spring 38, to the winding of the release magnet. It is clear that since relay B will always be actuated if relay A is actuated, 35 and that the traced releasing circuit includes resting contacts on both relays B and D, both relays D and A must be normal before an automatic release can take place. Therefore, if relay D is locked as set forth, due 40 to no ground being applied to wiper 34 from ahead after seizure, an automatic release cannot take place. The office attendant upon observing the condition of the selector in Fig. 1 will conclude what the condition is 45 and look to correcting the abnormal condition and, thereafter, release the locked selector into service. Of course, the office attendant in lieu of correcting the defect can put a false busy on the defective trunk and then 50 reinstate the engaging selector into service forthwith.

It is clear, now, that if a ground is not applied to bank contact 62 before the period of deactuation of relay B after its seizure 55 by wiper 34, if disengaged, the selector will lock and guard against seizure as set forth. It will also be clear that if the open condition assumed as on conductor 7 leading to conductor 204 were on the conductor 8 leading 60 to conductor 205 in lieu thereof the same operative condition would ensue because relay A² could not then actuate, as before. Also, if conductor 9 leading to conductor 206 were open, in lieu of the conductor 7 or 65 the conductor 8, no ground could be applied

back to wiper 34 engaging bank contact 62 before the period of deactuation of relay B after wiper 34 engaged bank contact 62, and therefore the same operative condition would ensue as when the circuit including conductors 7 and 8 were assumed open. That is to say, broadly, if a ground is not projected back to bank contact 62 after it, ungrounded, is seized by wiper 34 the selector in Fig. 1 will be incapacitated against automatic release, and the said selector, as well as the seized trunk will be guarded against seizure. 70

Incidental to the normal functioning of the selector Fig. 1 there is a brief period 75 wherein relays D and B are co-incidently 80 in an actuated condition. This occurs after relay D actuates and before relay B has had time to deactuate consequent thereto. Then, a path can be traced from ground-seeking cut-in tone source (designated "cut-in 85 tone"), conductor 92, armature 93, working contact 94, conductor 95, armature 96, working contact 97, conductor 98, conductor 75, working contact 73, armature 15, conductor 4, pre-selector wiper 14, conductor 2, telephone P, conductor 3, pre-selector wiper 13, conductor 5, armature 12, working contact 72, conductor 74, wiper 33, bank contact 61, conductor 8, conductor 205, armature 212, resting contact 211, conductor 210, upper winding of relay A² to grounded battery. The distinctive tone propagated by the said tone source will be audible to the calling party through the receiver until relay B deactuates and opens the path at working contact 97. This tone cannot be applied unless the selector has cut-in, so the tone will index the condition that the call progressed responsive to the sent impulses and that an inoperative element has not vitiated 90 the call, though, of course, the cut-in tone will be audible to the calling party if an open trunk is encountered, in like manner, the selector itself functioning normally up to and including its seizure of a disengaged 95 bank contact set. 100

It is clear that while a pre-selector K is shown in Fig. 1 between the calling telephone and the first selector, it is not necessary to employ a pre-selector, and that a 105 first selector may be provided specific to each line leading to a telephone as P. Also, in place of providing a line leading direct from the first selector to a telephone, the line may lead to a spring jack on a switchboard, and a switching plug provided to co-operate with the springjack. It is, of course, not new to provide springjack ended trunks leading directly to first selectors of 110 types heretofore known. 115

Under the conditions outlined above, that 120 is a springjack ended trunk leading directly to a specific selector as in Fig. 1, for example, if an open trunk is encountered, and therefore relay F remains normal, the tone ap- 125 130

plied to conductor 95 will be applied from armature 99 to resting contact 100 and to conductor 98, audible to the calling party (or the office attendant when listening-in) over the described cut-in tone path. The application of the cut-in tone will in the latter instance be continuous, thus indicating that a defective link has been encountered. Of course, if the first selector encounters a defective trunk under the condition of there being no pre-selector the calling party will not be able to call further until the office attendant restores the first selector, and he will know when this has been done, as the tone will be disconnected consequent to the restoration of the first selector. However, if the open trunk condition is encountered by the second (or a succeeding selector) this tone will not be heard due to the fact that when relay B² deactuates it introduces a lapse of ground potential to conductor 206 which causes relay D to deactuate and release the first selector.

Assuming that the call progressed normally, as hereinbefore described, up to the point of wipers 232, 233 and 234 seizing bank contacts 260, 261 and 262, but that trunk conductor 207 leading to connector Fig. 5 through holding circuit Fig. 3, is open at some point between bank contact 260 and the ground permanently applied to the lower winding of relay A⁵. In such event neither relay A⁵ nor its dependent relay B⁵ will actuate and ground conductor 514 as set forth. Also, relay A⁵ will not have current derived through it to attract armature 306 to ground conductor 303. Then, when relay B² deactuates, there having been no supplemental ground applied from conductor 303 no current will be derived through the inside winding of relay F² in maintaining relay D² and therefore relay F² will not actuate and lock as described. Relay F² remaining normal, when relay A² deactuates consequent to relay D² actuating (relay E² deactuating incident to the wipers attaining the first rotary position), a locking circuit for relay D² can be traced from grounded armature 218, resting contact 224, conductor 225, armature 226, working contact 284, outside winding of relay D², conductor 285, armature 282, resting contact 283, conductor 286, off-normal spring 241, spring 242, restricting resistance 287 to grounded battery. Armature 222 of relay B retracts from grounded working contact 221 a sufficient period before armature 288 engages resting contact 289 incident to the deactuation to create a lapse of ground on conductor 206 of sufficient period to allow the cut-off relay in the pre-selector K and also the relay D in the first selector Fig. 1 to deactuate, the latter relay closing the traced release magnet circuit to release the said first selector to normal. This deactuation of relay D taking place before the slow-pick-up relay G² can actuate because of the closed path from its winding to resting contact 289, armature 288, resting contact 281, armature 280, conductor 279, spring 239, to off-normal ground on spring 240, causing grounded armature 290' to engage working contact 291', applying the said ground to conductor 206. The latter grounding guards the selector Fig. 2 against seizure by a selector (perhaps the selector in Fig. 1 in a newly initiated call from telephone P), and due to relay D² being locked actuated the ground from armature 290' applied to conductor 206, attached conductor 271 applied to working contact 270, armature 268, conductor 267, conductor 266, armature 265, resting contact 290, conductor 263, wiper 234 will be applied to engaged bank contact 262. Thus, bank contact 262 (and its multiples) is guarded against seizure so long as the wiper 234 is in engagement, and prevents a second call being initiated due to encountering the open trunk. It is clear, now, that not only is the selector which encountered the defective trunk guarded against seizure, but the trunk seized is so guarded, and further, this guarded condition will exist until the selector is released manually by the office attendant, for the traced circuit including the release magnet will be open due to armature 226 being attracted from resting contact 227, relay D² being locked actuated.

Referring again to relay B², armature 265 and its resting contact 290 is so adjusted that when said 265 retracts from working contact 264 a lapse of short-circuit around the inside winding of relay F² will occur of sufficient duration to cause the relay F² to attract its armature 276 against its working contact 277, provided, of course, that wiper 234 receives ground from bank contact 262 following the seizure thereof. The inside winding of relay F² must be short-circuited at all times, except at the instant the armature 265 is retracting, otherwise if a selector wiper corresponding to 234 engages a bank contact multiplied with the guarded bank contact 262 the battery potential, carried on the private wiper of a normal selector while hunting will traverse the inside winding of relay F² in reaching conductor 206 over the path traced, causing said F² to actuate and thereby upset the guarded condition of its selector leading-in, as well as its selector engaged private bank contact, 62 and 262 respectively. This is assuming the selector has become primarily incapacitated due to the wiper 234 failing to receive ground from ahead. The armature 265 may be a double one to promote ease of adjustment (allowing one to retract, fol-

lowed by the other for example) to provide for the short-circuited lapse to the inside winding of relay F^2 .

In a normal connection, wherein relay F^2 actuates, and locks for the duration of the service, when the locking circuit is opened consequent to the shaft restoring and off-normal springs 239 and 240 disengage, relay D^2 is not locked through its outside winding and is therefore held actuated by the energization of its inside winding as described hereinbefore.

In view of the fact relay F^2 in any event is short-circuited for a period after relay D^2 energizes and closes its armature 226 into engagement with working contact 284, the traced locking path including the outside winding of relay D^2 will become closed and will therefore aid in attracting the armatures of said D^2 . Then, if relay F^2 actuates because of a normal seizure and the said locking path is opened the inside energized winding of D^2 will support the said relay D^2 actuated.

A normal release (as by calling party replacing receiver on the hookswitch) before the wipers have seized a bank contact and therefore under the condition of relays D^2 being normal and relays A^2 and B^2 restoring to normal will occur over the following energized path causing the release magnet (designated RLSE. M.) to actuate to unlock the shaft for restoration:—grounded armature 218, resting contact 224, conductor 225, armature 226, resting contact 227, conductor 228, armature 229, resting contact 291, spring 237, spring 238, to the winding of the release magnet. It is clear that since relay B^2 will always be actuated if relay A^2 is actuated, and that the traced releasing circuit includes resting contacts on both relays B^2 and D^2 , both relays D^2 and A^2 must be normal before an automatic release can take place. Therefore, if relay D^2 is locked as set forth, due to no ground being applied to wiper 234 from ahead after seizure, an automatic release cannot take place. The office attendant upon observing the condition of the selector in Fig. 1 will conclude what the condition is, and look to correcting the abnormal condition, and thereafter, release the locked selector into service. Of course, the office attendant in lieu of correcting the defect can put a false busy on the defective trunk and then reinstate the engaging selector into service forthwith.

It is clear, now, that if a ground is not applied to bank contact 262 before the period of deactuation of relay B^2 after its seizure by wiper 234, if disengaged, the selector will lock and guard against seizure as set forth. It will also be clear that if the open condition assumed as on conductor 207 leading to conductor 301 were on the conductor 208 leading to conductor 302 in lieu thereof the

same operative condition would ensue because relay A^3 could not then actuate, as before. Also, if conductor 209 leading to conductor 303 were open in lieu of the conductor 207 or the conductor 208, no ground could be applied back to wiper 234 engaging bank contact 262 before the period of deactuation of relay B^2 after wiper 234 engaged bank contact 262, and therefore the same operative condition would ensue as when the circuit including conductors 207 and 208 were assumed open. That is to say, broadly, if a ground is not projected back to bank contact 262 after it, ungrounded, is seized by wiper 234 the second selector Fig. 2 will be incapacitated against automatic release, and the said second selector, as well as the seized trunk, will be guarded against seizure.

Incidental to the normal functioning of the second selector Fig. 2 there is a brief period wherein relays D^2 and B^2 are coincidently in an actuated condition. This occurs after relay D^2 actuates and before relay B^2 has had time to deactivate consequent thereto. Then, a path can be traced from ground-seeking cut-in tone source (designated "cut-in tone") conductor 292, armature 293, working contact 294, conductor 295, armature 296, working contact 297, conductor 298, conductor 275, working contact 273, armature 215, conductor 204, conductor 7, bank contact 60, wiper 32, conductor 75, working contact 73, armature 15, conductor 4, pre-selector wiper 14, conductor 2, telephone P, conductor 3, pre-selector wiper 13, conductor 5, armature 12, working contact 72, conductor 74, wiper 33, bank contact 61, conductor 8, conductor 205, armature 212, working contact 272, conductor 274, wiper 233, bank contact 261, conductor 208, conductor 302, series winding of relay A^3 , conductor 304, conductor 513, resting contact 515, make-before-break spring 516, conductor 517, upper winding of relay A^5 to grounded battery. The distinctive tone propagated by the said tone source will be audible to the calling party through the receiver until relay B^2 deactuates and opens the path at working contact 297. This tone cannot be applied unless the second selector Fig. 2 has cut-in, so the tone will indicate the condition that the call progressed responsive to the sent impulses and that an inoperative selector element has not vitiated the call, though, of course, the cut-in tone will be audible to the calling party if an open trunk is encountered, in like manner, the selector itself functioning normally up to and including its seizing a disengaged bank contact set. Further, if an open trunk is encountered, and therefore relay F^2 remains normal, the tone applied to conductor 295 will be applied from armature 299 to resting contact 200 and to conductor 298, 130

audible to the attendant should he listen in on the trunk, over the described cut-in tone path. Of course, due to the described ground lapse occurring to conductor 206, the 5 first selector will be released, and also the pre-selector if one is employed as shown in Fig. 1.

Referring again to relay G², an office of which is to delay the effective application of 10 the traced ground from off-normal spring 240 through armature 288 and resting contact 289 to conductor 206. That is to say, in lieu of applying the conductor leading from resting contact 289 to conductor 206 it 15 is applied to the winding of the slow-pick-up relay G², and then the ground on its (G²) armature 290' is secondarily applied to working contact 291' and to conductor 206. Therefore, the delay occasioned by adjusting 20 armature 288 to engage resting contact 289 after armature 222 disengaged working contact 221 is augmented by the actuation period of relay G². This augmented delay 25 simplifies the adjustments of armature 288 and its resting contact 289 and insures that a ground lapse of sufficient duration exists from the ungrounding consequent to armature 222 retracting and the re-application of ground by the attracting of armature 290' to deenergize relay D of the first selector, causing the said first selector to release 30 to normal as described, and in turn release the pre-selector from it.

Consequent to the actuation of relay G², 35 which only occurs if wiper 234 does not receive ground from ahead after seizure as set forth, and relay B² deactuates consequent to the actuation and locking of relay D², grounded armature 292' engages working contact 293' causing lamp L² to glow.

Lamp L² (which may be common to a plurality of selectors) is located observable 40 to the exchange attendant, who will understand from its glowing that a selector is incapacitated as set forth.

Lamp L²' (which may be common to a plurality of selectors) will glow upon the first off-normal movement of the shaft, energized from grounded battery, resistance 287, 45 spring 242, spring 241, conductor 286, resting contact 283, armature 282, conductor 285 to ground through said L²'. It will extinguish only when relay F² receives ground from a normal trunk seized, or when the attendant restores the selector.

Condenser-resistance sets 94'-95' and 96'-97' and 98'-99' in Fig. 1; 294'-295' and 296'-297' and 298'-299' in Fig. 2 and 50 527-528 and 529-530 in Fig. 5 are for the purpose of absorbing spark current at the instant of circuit opening and is a well known device having no direct operative function in the switching elements.

Assuming the normal condition of the 55 traced circuit from telephone P through pre-

selector, first selector in Fig. 1, second selector in Fig. 2, holding circuit Fig. 3, connector Fig. 5. The connector Fig. 5 will be assumed as seized and with the shaft thereof in normal position; that is, relays A⁵ and B⁵ have actuated consequent to the seizure only. Under the assumed condition, relays D and F of Fig. 1 are actuated; relays D² and F² of Fig. 2 are actuated; relay A³ of Fig. 3 is actuated and relays A⁵ and B⁵ of Fig. 5 are actuated. As has been set forth, the circuit including the release magnet in Fig. 1 will become closed consequent to the deactuation of relay D. Likewise the circuit including the release magnet in Fig. 2 will 75 become closed consequent to the deactuation of relay D². The actuated condition of said D and D² is dependent upon ground maintained on conductor 303 in Fig. 3, which latter condition depends upon the actuated state of relay A³, which in turn, depends upon the current supplied from relay A⁵ to the calling telephone P. That is to say, the release magnet circuits of the first and the second selectors are held open by virtue of 80 the ground applied from relay A³ ahead; the latter now controlled by the state of the path through calling telephone P. So if the receiver at said P is replaced upon the hook-switch relay A³ will deactuate, its period after its consequent deenergization, and ground will thereby be removed from conductor 303, followed by the deactuation of relays D and 85 D² and the release to normal of the selectors in Figs. 1 and 2.

It is thus clear that the office of relay A³ is to maintain conductor 303 (which is joined to conductor 209) grounded while relay A⁵ (and its dependent relay B⁵) is held actuated, and consequently held grounded under 90 the condition of conductor 514 being grounded.

Assume, now, that Fig. 3 is removed and Fig. 5 is attached at the right of Fig. 2, conductors 207, 208 and 209 joining conductors 512, 513 and 514 respectively. This arrangement would be employed if the second selector, Fig. 2 is in the same exchange office as the connector Fig. 5, or at least where it is practicable to carry the private conductor 209 to the conductor 514 of the connector. The operation of Figs. 1, 2 and 5 will be the same as when Fig. 3 is employed because in lieu of conductor 209 receiving ground from conductor 303 in Fig. 3 it will 105 now receive it from conductor 514 in Fig. 5, it being clear from the foregoing that relays A³ and A⁵ must operate coincidently, if either operates, and relay B⁵ which controls the grounding of conductor 514, is in a directly dependent secondary relation to relay A⁵. Fig. 3 is thus only an expedient to 110 obviate carrying conductor 209 in Fig. 2 conductively to conductor 514 in Fig. 5.

Were the second selector Fig. 2 located in 115

a remote exchange office from Fig. 1, say in the same exchange office with Fig. 5, and conductors 207, 208 and 209 connect directly with conductors 512, 513 and 514 respectively, as referred to in the preceding paragraph, Fig. 3 may be introduced in the trunk between Figs. 1 and 2, conductors 7, 8 and 9 connecting with conductors 301, 302 and 303 respectively and conductors 301 and 10 304 connecting with conductors 204 and 205 respectively. Then, in view of relay A³ being in series relation with relay A², if a trunk conductor is open, neither relay A³ nor A² can actuate. That is, if relay A³ can 15 not actuate relay B² (dependent upon A²) cannot apply ground to conductor 206, and if relay A³ actuates relay A² will actuate. The condition of conductor 303 will thus correspond to the condition of conductor 20 206, the operation of which with respect to the functioning of the selector in Fig. 1 has been fully discussed hereinbefore.

If, now, in lieu of the first exemplified combination, that of Figs. 1, 2, 3 and 5, assume 25 that the repeater Fig. 4 is substituted for Fig. 3, (the lines extending to the left-hand margin of Fig. 4 registering with the lines extending to the right-hand margin of Fig. 2, and the lines extending to the right-hand 30 margin of Fig. 4 registering with the lines extending to the left-hand margin of Fig. 5, bearing in mind the repeater Fig. 4 is in the same exchange office with Fig. 2, remote from the office in which Fig. 5 is), the object 35 being to supply talking and receiver-exciting battery to the calling telephone P from the exchange office in which its line, terminating in pre-selector K extends, and, as before, the called telephone Q receives talking and receiver-exciting battery from the connector located in the office in which the called line 40 terminates. Where the trunk between Fig. 2 and Fig. 5 is long and of high ohmic resistance the current supplied the calling telephone will be too attenuated for satisfactory 45 service, hence the expedient of supplying the calling telephone locally from the repeater. The broad idea of supplying battery from the trunk repeater (and also reversing the 50 battery with relation to the flow through the calling telephone consequent to the current projected over the trunk from the connector being reversed) to the calling telephone is not new, however, the novel repeater Fig. 4 55 of the present invention, in addition to the said functions, has the novel capability of reflecting the condition of the out-going trunk circuit to the in-coming conductors thereof. That is, if the trunk out-going from Fig. 4, 60 or the circuit included thereby is open, the condition of the in-coming conductors to Fig. 4 will be changed because thereof consequent to the seizure of the repeater by the selector Fig. 2.

65 It will be assumed that the calling party

has initiated the call, sent the first two digits and the first and second selectors functioned and the second selector Fig. 2 has engaged and seized bank contacts 260, 261 and 262, as before set forth. However, in the assumed 70 instance the described telephonic path to said 260 and 261 will be continued from conductor 207 to conductor 410, make-before-break spring 415, resting contact 416, conductor 417 through lower winding of relay 75 A⁴ to ground, and from conductor 208 to conductor 411, make-before-break spring 418, resting contact 419, conductor 420, through upper winding of relay A⁴ to grounded battery. Relay A⁴ will actuate from the current supplied through its windings and traced circuits back, including the calling telephone. Grounded armature 421 engages working contact 422 which extends to the winding of slow-releasing relay B⁴, causing 80 it to actuate. A closed circuit path may be now traced from grounded lower winding of relay A⁵ of Fig. 5, conductor 520, spring 519, resting contact 518, conductor 512, conductor 413, conductor 423, working contact 424, 85 armature 425, conductor 426, winding 427 of slow-releasing relay E⁴, conductor 428, resting contact 429, make-before-break spring 430 of relay D⁴, conductor 431, inside 90 winding of relay F⁴, conductor 432, resting contact 433, armature 434, conductor 435, working contact 436, armature 437, conductor 438, conductor 414, conductor 513, resting contact 515, make-before-break spring 516, conductor 517 through upper winding of relay 95 A⁵ to grounded battery; relay A⁵ actuating, followed by its dependent relay B⁵. Relay E⁴ will also actuate under the influence of energized winding 427. Grounded 100 armature 439 engages working contact 440 attached to conductor 441, extending to working contact 442, armature 443, conductor 444, to conductor 412, conductor 209 leading to bank contact 262 engaged by wiper 234. Thus, relays D², D and the line cut-off 105 relay in pre-selector K will be maintained as in the case of relay A³ actuating and accomplishing the same condition before described. Armature 443 applies the ground received 110 from armature 439 to working contact 445, conductor 446, through outside polarizing winding of relay F⁴ to grounded battery. At this juncture relays A⁴, B⁴ and E⁴ are 115 actuated, the relay F⁴ not being sufficiently energized to actuate.

Upon the calling party sending the third digit "2" as before, relay A⁴ will deactuate twice and reactivate, opening the path described including relay A⁵ of Fig. 5 at working contact 424 two times. Grounded armature 421 retracts twice against resting contact 445, which communicates the ground to armature 446, working contact 447 to winding of slow-releasing relay C⁴, causing said 125 C⁴ to actuate and so maintain until its period 130

after the last retraction and subsequent attraction of armature 421. Armature 434 will engage working contact 448 connected to conductor 426, which by closing an alternate path removes from the traced path including relay A⁵ the winding 427 of relay E⁴ and the inside winding of relay F⁴. The current which existed in the two windings of relay F⁴ energized it opposingly. The relay 5 F⁴ is designed and adjusted to actuate only when the two windings thereon are energized cumulatively. Relay E⁴ will deactivate its period after relay C⁴ actuates, and to guard against a lapse of ground on conductor 412 at this juncture armature 450 on relay C⁴ engages ground on its working contact 451, applying it to conductor 441 to replace the ground removed from working contact 440. Armature 450 is adjusted to 10 remain engaged until after contact 433 is engaged upon the deactuation of relay C⁴ to insure relay E⁴ actuating before armature 450 disengages grounded working contact 451 to provide against a lapse of ground on conductor 412 at the end of the series of two 15 impulses of a duration which would cause relays D², D and the line cut-off relay in pre-selector K to deactivate. The same applies to any subsequent series of impulses sent 20 from the calling telephone, and which will control relay A⁵ primarily. Relay A⁵ will deactivate and reactivate two times as when the third digit is sent as exemplified hereinbefore and the connector Fig. 5 will function 25 the same, consequent thereto. The same cycle of operations described will take place, when the last digit "2" is sent, bearing in mind that the connector steps vertically in response to the third digit series and 30 rotarily in response to the last digit series. That is to say the control of connector Fig. 5 is the same with Fig. 4 intervening as with Fig. 3 assumed before.

If either trunk conductor 413 or 414 were 35 open, or in fact the circuit described including relay A⁵ and the winding 427 of relay E⁴, it is clear conductor 412 cannot become grounded for unless a closed circuit condition of the trunk exists when the trunk leading to Fig. 5 from Fig. 4 is seized by second selector Fig. 2, and, as before, if a ground is not projected back to bank contact 262 consequent to the seizure of the 40 trunk the second selector Fig. 2 will become incapacitated.

Upon the called party responding, relay D⁵ will be caused to actuate and reverse the direction of current to the trunk conductors 512 and 513 in a manner well known in connectors of the type of Fig. 5. The current 45 derived from winding of relay A⁵ traversing trunk conductor 414, conductor 438, armature 437, working contact 436, conductor 435, armature 434, resting contact 433, conductor 432 inside winding of relay F⁴ con-

ductor 431, spring 430, resting contact 429, conductor 428, winding 427 of relay E⁴, conductor 426, armature 425, working contact 424, conductor 423, to trunk conductor 413 will therefore be reversed, the inside winding 50 of relay F⁴ magnetizing its core cumulatively with the outside winding, so relay F⁴ will actuate. Armature 452 engages grounded working contact 453 grounding conductor 454 leading to winding of relay 55 D⁴. Relay D⁴ will actuate, armatures 455 and 456 engaging make-before-break springs 418 and 415 and disengaging resting contacts 419 and 416 respectively. Also, armature 457 engages make-before-break spring 60 430 and disengages resting contact 429. The direction of current projected to the calling telephone P from windings of relay A⁴ will be reversed as regards the normal state, as the said windings will be related to conductors 410 and 411 reciprocally to normal. Armature 458 on relay F⁴ engages working contact 459, which locks the inside winding 65 of said F⁴, to conductor 435 irrespective of state of relay C⁴. The telephonic path from conductor 411 to conductor 414 includes condenser 460 and conductor 438, and the telephonic path from conductor 410 to conductor 413 includes condenser 461, conductor 426, armature 462, working contact 463. A 70 bridged path from conductor 438, armature 437, working contact 436, working contact 459, armature 458, inside winding of relay F⁴, conductor 431, spring 430, armature 457, winding 464 and winding 427 of relay E⁴ 75 extends to conductor 426.

Upon called party hanging the receiver on the hook-switch relay D⁵ will restore to normal and cause the current to traverse the said bridged path in the normal direction 80 whereupon relay F⁴ will deactivate, as it is designed to do when its windings are energized oppositely. Relay D⁴ will deactivate 85 consequent thereto, and restore the current flow to the calling telephone P to normal 90 direction. If the calling party hangs the receiver on the hookswitch first, relays A⁴ and B⁴ will restore opening the holding ground on conductor 412 which will deenergize relays D and D², causing the first and 95 second selectors controlled by them respectively to restore to normal, and due to opening the said bridge path, relays A⁵ and B⁵ will deactivate and prepare the connector for 100 releasing when the receiver on the called 105 telephone is returned to the hookswitch.

Were Fig. 4 introduced between Figs. 1 and 2 so the lines running to the margins register, Fig. 2 connected direct to Fig. 5, the interoffice trunk extending from the repeater 110 Fig. 4 to second selector Fig. 2, the repeater would function in the manner described for not only the second and third digits, but also the fourth digit "1", the outgoing circuit of 115 the repeater having the same relation to a 120 125 130

selector ahead as the sending device or the hookswitch on the calling telephone has to the first selector.

- From the foregoing it is clear that if the 5 private wiper (34 or 234) of a selector does not receive ground from ahead after it engages and seizes an ungrounded bank contact the said selector will be incapacitated. Therefore, if because of any operative defect 10 in the said selector after the switching relay (D or D²) receives energizing battery from the interrupter relay (E or E²) and the release relay (B or B²) deactuates the said selector will be incapacitated if its said 15 private wiper does not receive ground after the actuation of the switching relay (D or D²) and before the release relay (B or B²) deactuates its period after the switching relay actuates. So the selectors of the present 20 invention are not only adapted to become incapacitated and guarded against subsequent seizure when an open trunk conductor or private or other condition, such as a defective condition ahead which prevents normal 25 operation of applying ground back to the private wiper of a seizing selector, but the selectors are adapted to similarly function upon a said selector not functioning normally and completely. For example, if the 30 selector after effecting a vertical movement and obtains a rotary movement fails to seize an operative trunk the selector will become incapacitated and guarded as set forth. In this connection it may be stated that should 35 the calling party replace the receiver on the hookswitch during the process of transmitting impulses from the sending device 17 the selector would not receive a rotary impulse incident to the line relay (A or A²) deactuating, because the slow-releasing period of 40 the release relay (B or B²) will be shorter than that of the series relay (C or C²), and therefore, the selector would be restored through the agency of the release magnet 45 before the rotary magnet of the selector would receive an operative impulse consequent to the deactuation of the series relay, causing the wipers to engage the first set of bank contacts.
- 50 The alternative relations of the figures assumed may all occur in the same exchange system depending upon the distance apart of exchange offices and the routing of a call; the latter referring to whether the call is 55 destined to a telephone in the same exchange office, or to a remote exchange office, or to a more remote exchange office. The assumed alternate arrangement seems the simplest and the most practical way of setting forth 60 the objects, operation and organization of the invention applied to a comprehensive exchange system.

It is clear from the foregoing that the 65 number of numerical orders which the exchange may employ may be increased or de-

creased from that described, and further, that the first selector in Fig. 1 may be interchanged with the second selector Fig. 2, or all selectors used may be of either type, or 70 selectors of well known type may be introduced. However, the functioning of the latter, if employed, will be unchanged. Further, the mode of controlling the switches, as by indirect automatic or manual control means is of secondary importance in 75 carrying out the present invention to possible adaptations of it. Moreover, the elements may be widely modified mechanically and electrically in applying the invention broadly by those skilled in the art, all without departing from the scope of the present invention as set forth in the system chosen for its illustration herein in view of the annexed claims.

I claim:—

1. In an automatic telephone system, a switch terminating a link consisting of telephonic conductors and a private conductor for inclusion in a temporary connection including a successive link between a calling and a called line, means for controlling the switch, and automatically applied means for incapacitating the switch against the control means if the link engaged by the switch has an open private path without restoring the switch from the engaged line.

2. In an automatic telephone system, a switch terminating a link consisting of telephonic conductors and a private conductor for inclusion in a temporary connection including a successive link between a calling and a called line, means for controlling the switch, and automatically applied means for incapacitating the switch against the control means if the link engaged by the switch has either an open telephonic path, or an open private path without restoring the switch from the engaged line.

3. In an automatic telephone system, a switch terminating a link consisting of telephonic conductors and a private conductor for inclusion in a temporary connection including a successive link between a calling and a called line, remote means for operating and releasing the switch, and automatically applied means for incapacitating the switch against releasing when operated, by remote control if the link engaged by the switch has an open private path while maintaining the switch operated.

4. In an automatic telephone system, a switch terminating a link consisting of telephonic conductors and a private conductor for inclusion in a temporary connection including a successive link between a calling and a called line, remote means for operating and releasing the switch, and automatically applied means for incapacitating the switch against releasing when operated, by remote control if the link engaged by the switch

has an open telephonic path, or an open private path while maintaining the switch operated.

5. In a telephone system, a switch terminating a link for inclusion in a temporary connection including a successive link between a calling and a called line, means on the calling line to control movement of the switch in effecting the said connection and for restoring the switch, and automatically applied means for incapacitating the switch against the restoring means if the link engaged by the switch has an open telephonic path while maintaining the switch operated.

15. 6. In a telephone system, a switch terminating a link consisting of telephonic conductors and a private conductor for inclusion in a temporary connection including a successive link between a calling and a called line, means on the calling line to control movement of the switch in effecting the said connection and for restoring the switch, and automatically applied means for incapacitating the switch against the restoring means if the link engaged by the switch has an open private path while maintaining the switch operated.

7. In a telephone system, a switch terminating a link consisting of telephonic conductors and a private conductor for inclusion in a temporary connection including a successive link between a calling and a called line, means on the calling line to control movement of the switch in effecting the said connection and for restoring the switch, and automatically applied means for incapacitating the switch against the restoring means if the link engaged by the switch has either an open telephonic path, or an open private path while maintaining the switch operated.

45. 8. In a telephone system, a calling line leading to a pre-selector having access to a first trunk leading to a switch, means on the calling line to initiate a functioning of the pre-selector which will cause it to seize the said trunk if idle, means on the calling line to effect step-by-step control of the switch to effect a connection with an idle second trunk leading to a switch, means on the calling line for restoring the first said switch, and automatically applied means to incapacitate the first said switch against restoring under control of the means on the calling line if the second trunk has an open circuit condition to the first said switch while maintaining the switch operated.

60. 9. In a telephone system, a calling line leading to a pre-selector having access to a first trunk leading to a switch, means on the calling line to initiate the functioning of the pre-selector which will cause it to seize the said trunk if idle, means on the calling line to effect step-by-step control of the switch to effect a connection with an idle second trunk leading to a switch and to also effect

step-by-step control of the second said switch in forming a connection between the calling line towards a called line, means of control on the calling line for restoring the switches and the pre-selector, and automatically applied means to incapacitate the first said switch against restoring under control of the means on the calling line if the second trunk presents an open circuit condition to the first said switch while maintaining the 75 switch operated.

10. In a telephone system, a calling line leading to a pre-selector having access to a first trunk leading to a switch, means on the calling line to initiate the functioning of the 80 pre-selector which will cause it to seize the said trunk if idle, other trunks each leading to a switch, means on the calling line to control the step-by-step movement of the said switches including the first said switch to 85 effect connection with the trunks successively, forming a train of switch-terminating trunk links extending from the pre-selector towards the called line, means of control on the calling line for restoring the 90 switches controlled and the pre-selector, and automatically applied means to incapacitate against release under control of the calling line any said switch terminating a trunk which is in a seized relation to a succeeding 95 trunk if the seized trunk presents an open circuit condition while maintaining the switch operated.

11. In an automatic telephone system, a plurality of lines, means for establishing 100 connection between two of said lines, said means including a trunk line having a pair of leading-in line contacts and a leading-in private contact, and automatically applied means for placing a permanent guarding potential on said private contact consequent to its seizure when one of the conductors of said trunk is abnormally open, to thereby prevent the said trunk being thereafter seized, whereby said potential cannot be removed except by local release of the line.

45. 12. In a telephone system, a plurality of trunk lines and an automatic switch for seizing any one of said trunk lines, a leading-in trunk line for the switch, means for propelling said switch to an idle trunk line, means for stopping the said switch on said idle trunk line, means controlled over the leading-in trunk for restoring the operated switch to normal, and a relay for rendering the switch incapacitated against trunk-controlled restoring, and means automatically applied for effectively operating the relay if a conductor of the idle trunk on which the switch stopped has an open conductor.

60. 13. In an automatic telephone system, a switch terminating a link for cooperating with a successive link having leading-in conductors consisting of a pair of line conductors and a private conductor and outgoing 130

conductors consisting of a pair of line conductors leading to a second switch, a leading-in and a called line, means for controlling the selective movement of the first switch in effecting the said cooperation, means for restoring the said first switch, means in the successive link for grounding the private conductor if the link seized is normal and for not grounding the private conductor if a leading-in or the out-going line conductor of the successive link is open, and automatically applied means in the first switch for incapacitating it against releasing if the said private conductor does not become grounded following the seizure of the successive link.

14. In an automatic telephone system, a switch terminating a link for cooperating with a successive link having leading-in conductors consisting of a pair of line conductors and a private conductor, means including a closed path over the line conductors for applying a ground to the private conductor following its seizure by the switch, means for controlling the operation of the switch, and automatically applied means in the switch to incapacitate it against the control means if the private conductor does not present a grounded condition following its seizure by the switch.

15. In a telephone system, a calling line leading to a pre-selector having access to a first trunk leading to a switch, means on the calling line to initiate the functioning of the pre-selector which will cause it to seize the said trunk if idle, means on the calling line to effect step-by-step control of the switch to effect a connection with an idle second trunk leading to a switch and to also effect step-by-step control of the second said switch in forming a connection between a calling line towards a called line, means of control on the calling line for restoring the switches and the pre-selector, and automatically applied means to incapacitate the first said switch against restoring under control of the calling line and to also apply a false busy condition to the first trunk if the second trunk presents an open circuit condition to the first said switch while maintaining the first switch operated and after the other said switches are restored.

16. In a telephone system, a calling line leading to a pre-selector having access to a first trunk leading to a switch, means on the calling line to initiate the functioning of the pre-selector which will cause it to seize the said trunk if idle, other trunks each leading to a switch, means on the calling line to control the step-by-step movement of the said switches including the first said switch to effect connection with the trunks successively, forming a train of switch-terminating trunk links extending from the pre-selector towards the called line, means of con-

trol on the calling line for restoring the switches controlled and the pre-selector, and automatically applied means to incapacitate against release under control of the calling line any said switch terminating a trunk which is in a seized relation with a succeeding trunk and to also apply a false busy condition to the trunk leading to the seizing switch if the seized trunk presents an open circuit condition to the seizing switch.

17. In a telephone system, a switch terminating a link for inclusion in a temporary connection including a successive link between a calling and a called line, means for controlling the switch, and automatically applied means for incapacitating the switch against the control means and for applying a false busy condition to the link leading to the said switch and to the successive link seized by the switch if the successive link has an open telephonic path.

18. In a telephone system, a switch terminating a link for inclusion in a temporary connection including a successive link between a calling and a called line, means for controlling the switch, and automatically applied means for incapacitating the switch against the control means and for applying a false busy condition to the link leading to the said switch and to the successive link seized by the switch if the successive link has an open private path.

19. In a telephone system, a switch terminating a link for inclusion in a temporary connection including a successive link between a calling and a called line, means for controlling the switch, and automatically applied means for incapacitating the switch against the control means and for applying a false busy condition to the link leading to the said switch and to the successive link seized by the switch if the successive link has an open telephonic path, or an open private path.

20. In a telephone system, a switch terminating a link for inclusion in a temporary connection including a successive link between a calling and a called line, remote means for controlling the switch, and automatically applied means for incapacitating the switch against releasing by remote control and for applying a false busy condition to the link leading to the said switch and to the successive link seized by the switch if the successive link seized is open.

21. In a telephone system, a calling line leading to a pre-selector having access to a first trunk leading to a switch, means on the calling line to initiate the functioning of the pre-selector which will cause it to seize the said trunk if idle, means on the calling line to effect step-by-step control of the switch to effect a connection with an idle second trunk leading to a switch and to also effect step-by-step control of the second said

switch in forming a connection between a calling line towards a called line, means of control on the calling line for restoring the switches and the pre-selector, and automatically applied means to incapacitate the specific first said switch solely against restoring under control of the calling line and to also apply a false busy condition to the first trunk and to the second trunk if the second trunk presents an open circuit condition to the first said switch.

22. In a telephone system, a calling line leading to a pre-selector having access to a first trunk leading to a switch, means on the calling line to initiate the functioning of the pre-selector which will cause it to seize the said trunk if idle, other trunks each leading to a switch, means on the calling line to control the step-by-step movement of the said switches including the first said switch to effect connection with the trunks successively, forming a train of switch-terminating trunk links extending from the pre-selector towards the called line, means of control on the called line for restoring the switches controlled and the pre-selector, and automatically applied means to incapacitate against release under control of the calling line only the switch terminating a trunk which is in a seized relation with a succeeding trunk and to also apply a false busy condition to the trunk leading to the seizing switch and to the trunk seized if the seized trunk presents an open circuit condition to the seizing switch.

23. In a telephone system, a plurality of trunk lines and an automatic switch for seizing any one of said trunk lines, means for propelling said switch to an idle trunk line, a relay for rendering only the specific switch incapacitated against releasing and for applying a guarding potential on the said trunk line and to the trunk line leading to the said switch, automatically applied means for effectively operating the relay if a conductor of the seized trunk is open.

24. In a telephone system, a switch terminating a link for inclusion in a temporary connection including a successive link leading from a calling line towards a called line, means for controlling the switch, a signal device, and automatically applied means for incapacitating only the specific switch against the control means and for causing the signal device to display if the link engaged by the switch has an open circuit condition.

25. In a telephone system, a calling and a called line, trunk links each terminating in a linking switch, means for directly operating the switches in establishing a connection with the calling to the called line, means on the calling line for restoring the switches concerned in the connection, and automatically

applied means to disable only a specific one 65 of said switches against said releasing upon it encountering a defective trunk link.

26. In a telephone system, a calling and a called line, trunk links each terminating in a linking switch, means for directly operating the switches in establishing a connection from the calling to the called line, means on the calling line for restoring the switches concerned in the connection, automatically applied means to disable only a specific one of 75 said switches against said releasing upon it encountering a defective trunk link, and means in the said disabled switch automatically responsive to its disablement wherein it will cause the restoration of antecedent 80 switches thereto in the connection.

27. In a telephone system, a switch terminating a link for inclusion in a temporary connection including a successive link leading from a calling line towards a called line, 85 means for controlling the switch, a signal device, and means for causing the signal device to display upon the first off-normal step of the switch and extinguish only upon the switch seizing a normally operative successive link.

28. In a telephone system, a switch terminating a link for forming a temporary connection between a calling and a called line, means on the calling line for controlling a 95 primary movement of the switch, automatic means for initiating a secondary movement thereof for selecting an idle trunk for extending the connection towards the called line, a tone source, and means for automatically maintaining the application of the tone source to the telephonic conductors leading toward the calling line made operative consequent to the switch seizing a trunk presenting an open circuit condition. 100

29. In a telephone system, a switch terminating a link for forming a temporary connection between a calling and a called line, means on the calling line for controlling the movement of the switch in selecting an idle 110 trunk for extending the connection towards the called line, a tone source, and means for automatically maintaining the application of the tone source to the telephonic conductors leading towards the calling line made operative consequent to the switch seizing an open trunk. 115

30. In a telephone system, a switch terminating a link for forming a temporary connection between a calling and a called line, means on the calling line for controlling a primary movement of the switch, automatic means for initiating a secondary hunting movement thereof for selecting and seizing an idle trunk for extending the connection towards the called line, a tone source, and automatically applied means for momentarily applying the tone source to the tele- 120

phone conductors leading toward the calling line consequent to the switch seizing the selected trunk.

31. In a telephone system, a switch terminating a link for forming a temporary connection between a calling and a called line, means on the calling line for controlling the movement of the switch in selecting and seizing an idle trunk for extending the connection towards the called line, a tone source, and automatically applied means for momentarily applying the tone source to the telephone conductors leading towards the calling line consequent to the switch seizing the selected trunk.

32. In a telephone system, a switch terminating a link for forming a temporary connection between a calling line and a called line, means on the calling line for controlling a primary movement of the switch, automatic means for initiating a secondary hunting movement thereof for selecting an idle trunk for extending the connection towards the called line, a tone source, automatically applied means for applying the tone source to the telephonic conductors leading toward the calling line if the switch after completing its primary movement does not normally selectively function to seize an idle trunk and means made effective incidental to applying the tone source for disabling the switch from thereafter hunting.

33. In a telephone system, a switch terminating a link for forming a temporary connection between a leading-in line and a called line, means on the leading-in line for controlling the movement of the switch for selecting a group of trunks and thereupon hunting over the group to seize the first idle trunk thereof for extending the connection towards the called line, a tone source, and automatically applied means for applying the tone source to the telephonic conductors leading towards the calling line if the switch after completing its selective movement does not operatively seize the selected trunk in the hunting movement.

34. In a telephone system, a switch terminating a link for forming a temporary connection between a leading-in line and a called line, means on the leading-in line for controlling the movement of the switch for selecting a group of trunks and thereupon hunting over the group to seize the first idle trunk thereof for extending the connection towards the called line, a tone source, and automatically applied means for applying the tone source to the telephonic conductors leading towards the calling line if the switch after starting its selective movement does not operatively seize the trunk regardless of whether the group is selected.

35. In a telephone system, a switch terminating a link for cooperation with a successive link including an automatic impulse

repeater therein joining the incoming with the outgoing section of the successive link, the incoming and outgoing sections not being conductively connected together, a calling and a called line, means on the calling line for controlling the movement of the switch in effecting the said cooperation and for restoring the switch, and automatically applied means for incapacitating the switch against the restoring means if the incoming section of the cooperated link leading to the repeater has an open telephonic path, or if the outgoing section of the link leading from the repeater has an open telephonic path.

36. In a telephone system, a switch terminating a link for cooperation with a successive link including an automatic impulse repeater therein joining a near with a remote section of the successive link, the incoming and outgoing sections not being conductively connected together, a calling and a called line, means on the calling line for controlling the movement of the switch in effecting the said cooperation and for restoring the switch, and automatically applied means for incapacitating the switch against the restoring means if the remote section of the cooperated link leading from the repeater has an open telephonic path.

37. In a telephone system, a first switch terminating a link for cooperation with a successive link including an automatic impulse repeater therein joining a near with a remote section thereof, the incoming and outgoing sections not being conductively connected together, a second switch at the far terminal of the remote section, a calling and a called line, means on the calling line for controlling the movement of the first switch in effecting the said cooperation in extending a connection from the calling line towards the called line through the second switch and for restoring the first switch, and automatically applied means for incapacitating the first switch against the restoring means if the remote section of the cooperated link leading from the repeater and extending to the second switch has an open telephonic path.

38. In a telephone system, a switch terminating a link for cooperation with a successive link including an automatic repeater therein joining a near with a remote section thereof, the incoming and outgoing sections not being conductively connected together, a second switch at the far terminal of the remote section, a calling and a called line, means on the calling line for controlling the movement of the first switch in effecting the said cooperation in extending a connection from the calling line towards the called line through the second switch and for restoring the first switch, and automatically applied means for incapacitating the first switch against the restoring means if a conductor

of the near section of the cooperated link leading to the repeater has an open circuit condition.

39. In a telephone system, a switch terminating a link for cooperating with a successive link including a repeater therein joining a near with a remote section of the successive link, the near and remote sections not being conductively connected together, a leading-in and a called line, means on the leading-in line for controlling the operative movement of the switch in effecting the said cooperation, means for restoring the switch, and further means automatically applied for incapacitating the switch against the restoring means if the cooperated said successive link is open.

40. In a telephone system, a switch terminating a link for cooperating with a successive link including a repeater therein joining a near with a remote section of the successive link, the near and remote sections not being conductively connected together, a leading-in and a called line, means on the leading-in line for controlling the operative movement of the switch in effecting the said cooperation, means for restoring the switch, and automatically applied means in the repeater for causing the near section of the successive link to present an open condition to the antecedent selector when testing if the remote section thereof presents an open condition.

41. In a telephone system, a switch terminating a link for cooperating with a successive link including a repeater therein joining a near with a remote section of the successive link, the near and remote sections not being conductively connected together, a leading-in and a called line, means on the leading-in line for controlling the operative movement of the switch in effecting the said cooperation, means for restoring the switch, and automatically applied means in the repeater for causing the switch to be incapacitated against releasing if the remote section thereto presents an open condition when cooperated.

42. In a telephone system, a switch terminating a link for cooperating with a successive link having near and remote sections joined by a repeater, the near section constituting a pair of line conductors and a private conductor, and the remote section having a pair of line conductors only, the near and remote sections not being conductively connected together, a leading-in and a called line, means on the leading-in line for controlling the operative movement of the switch in effecting the said cooperation, automatically applied means for restoring the switch, means in the repeater for causing the private conductor of the near section to present an open condition if the remote section presents an open condition, and means

for causing the switch to be incapacitated against releasing if the private conductor of the near section presents an open condition.

43. In a telephone system, a switch terminating a link for cooperating with a successive link including a repeater therein joining a near with a remote section of the successive link, the near and remote sections not being conductively connected together, a leading-in and a called line, means on the leading-in line for controlling the operative movement of the switch in effecting the said cooperation, means for restoring the switch, a tone source, and automatically applied means in the repeater for causing the switch to specifically operate to apply the tone source to the leading-in line if the remote section thereto presents an open condition.

44. In a telephone system, a switch terminating a link for cooperating with a successive link having near and remote sections joined by a repeater, the near section constituting a pair of line conductors and a private conductor, and the remote section constituting a pair of line conductors only, the near and remote sections not being conductively connected together, a leading-in and a called line, means for controlling the operative movement of the switch in effecting the said cooperation, means for restoring the switch, a tone source, and means in the repeater for causing the switch to continuously apply the tone source to the leading-in line if the remote section thereto presents an open condition.

45. In a telephone system, a calling and a called line, trunk links, each terminating in a linking switch, means for directly operating the switches in establishing a connection from the calling to the called line, means on the calling line for restoring the switches concerned in the connection, automatic means to disable only a specific one of said switches against said releasing consequent upon it encountering a defective trunk link, means in the said disabled switch automatically responsive to its disablement wherein it will cause the restoration of antecedent switches thereto in the connection, and further means in the said disabled switch to guard itself against subsequent seizure.

46. In a telephone system, a calling and a called line, trunk links each terminating in a linking switch, means for directly operating the switches in establishing a connection from the calling to the called line, means on the calling line for restoring the switches concerned in the connection, automatic means to disable only a specific one of said switches against said releasing consequent upon it encountering a defective trunk link, means in the said disabled switch automatically responsive to its disablement wherein it will cause the restoration of ante-

- cedent switches thereto in the connection, further means in the said disabled switch to guard itself against subsequent seizure and to guard the succeedent said defective trunk 5 against seizure thereafter.
47. In a telephone system, a calling and a called line, trunk links each terminating in a linking switch, means for directly operating the switches in establishing a connection from the calling to the called line, means on the calling line for restoring the switches concerned in the connection, automatic means to disable only a specific one of said switches against said releasing consequent upon it encountering a defective trunk link, means in the said disabled switch automatically responsive to its disablement wherein it will cause the restoration of antecedent switches thereto in the connection, 10 further means in the said disabled switch to guard itself against subsequent seizure, and a signal device which will evidence the condition.
48. In a telephone system, a calling and a called line, trunk links each terminating in a linking switch, means for directly operating the switches in establishing a connection from the calling to the called line, means on the calling line for restoring the 15 switches concerned in the connection, automatic means to disable only a specific one of said switches against said releasing consequent upon it encountering a defective trunk link, and a signal device which will 20 evidence the disablement.
49. In a telephone system, a calling and a called line, trunk links each terminating in a linking switch, means for directly operating the switches in establishing a connection from the calling to the called line, means on the calling line for restoring the 25 switches concerned in the connection, automatic means to disable only a specific one of said switches against said releasing consequent upon it encountering a defective trunk link, means in the said disabled switch automatically responsive to its 30 disablement wherein it will cause the restoration of antecedent switches thereto in the connection, and a signal device which will 35 evidence the condition.
50. In an automatic telephone system, a switch terminating a trunk link for cooperating with a successive link consisting of a pair of talking and operating conductors and a private conductor, means including a closed path over the talking and operating conductors for energizing the private conductor to maintain the switch operated following its seizure by the switch, manually controlled restoring means applied over the first said link for effecting the restoration of the operated switch, and automatically applied means effective to incapacitate the 40 switch against the restoring means and for 45 maintaining the switch operated if the private conductor does not present an energized condition to the switch following its seizure by the switch.
51. In a telephone system, a calling and 50 called lines, trunk links each terminating in a linking switch, means for directly operating the switches in establishing a connection consisting of a train of trunk links from the calling line to the called line, means on the calling line for restoring the switches concerned in the connection, automatically applied means to disable only a specific one of said switches against restoring upon it 55 connecting to a defective trunk link, and automatically applied means operative consequent to the connection to a defective trunk link for barring the defective trunk link from being thereafter connected with.
52. In an automatic telephone system, a calling line and terminating switch, a trunk link and terminating switch, a second line, means for directly operating the first said switch to connect the calling line with the trunk link, means for then operating the second said switch to extend the calling line to the said second line, means controlled from the calling line for restoring the switches, and automatically applied means effective 60 dependent upon the connected said second line being defective for disabling the trunk line switch from restoring from the second line while the calling line switch will normally restore from the trunk line.
53. In an automatic telephone system, a calling line and terminating switch, a trunk link and terminating switch, a second line, means for directly operating the first said switch to connect the calling line with the trunk link, means for then operating the second said switch to extend the calling line to the said second line, means controlled from the calling line for restoring the 65 switches, automatically applied means effective dependent upon the connected said second line being defective for disabling the trunk line switch from restoring from the second line while the calling line switch can be normally restored from the trunk link under control of the calling line, and automatically applied means effective consequent to the connection to the connected second line if the said second line is defective for barring the trunk line against being thereafter connected with by the first said switch.
54. In an automatic telephone system, a calling line and terminating switch, a plurality of trunk links, each trunk link having a terminating switch, the trunk links accessible from the first said switch, a second line, means for directly operating the said first switch to connect the calling line with a trunk link and for then operating the corresponding trunk link switch to extend the calling line to the said second line, means

- controlled from the calling line for restoring the connected switches, automatically applied means effective dependent upon the connected said second line being defective 5 when connected with for disabling the trunk link switch from restoring from the second line while the calling line switch will normally restore from the connected trunk link responsive to control from the calling line, 10 means for again directly operating the calling line switch to connect with another said trunk link and for operating the last connected trunk link terminating switch for connection to the second line, and an automatically applied means made effective consequent to the first connection to the second line dependent upon the second line then being defective for thereafter barring the second line against being connected with by 15 said another trunk link switch.
55. In an automatic telephone system, a calling line and terminating switch, trunk links and terminating switches respectively, a second line, means on the calling line for directly operating the first said switch to connect with a trunk link and for then directly operating the connected trunk link switch to extend the connection to the second line, manual control means on the calling line for destroying the connection and for thereafter at will directly effecting a reconnection from the calling line to the second line including a said trunk link, and automatically applied means effective consequent to the second line being defective when first connected to for barring it against being thereafter connected to.
56. In an automatic telephone system, a calling line and terminating first switch, a 40 permanently paired two-section trunk leading from the first switch to a second switch, the trunk section leading from the first switch consisting of a pair of talking conductors and a private conductor, the trunk section leading to the second switch consisting of only two talking conductors, mechanism interposed between the trunk sections for joining the sections, means controlled from the calling line for restoring the first switch from the trunk, and automatically applied means effective dependent upon a defective condition of either section of the trunk for disabling the restoring means.
57. In a telephone system, a connective switch, a signal device, line terminals consisting of a pair of talking terminals and a private terminal, means for seizing the switch and then automatically operating the switch from its normal position when seized into connection with the line terminals, line conductors leading from said line terminals consisting of a pair of normally closed circuit talking conductors and a private conductor, means whereby the condition of the terminal of the private conductor is determined from the talking terminals over the talking conductors, means for causing the signal device to display consequent to the switch moving from said normal position to connect with the called line terminals, 70 and automatically applied means responsive only to the switch connecting with the terminals and all said conductors are normally disposed with respect to other said conductors for effacing the signal. 75
58. In a telephone system, a connective switch, a tone source, line terminals consisting of a pair of talking terminals and a private terminal, leading-in terminals for the switch, means for seizing the switch through the leading-in terminals and then automatically operating the switch into connection with the line terminals, line conductors leading from said line terminals consisting of a pair of normally closed circuit talking conductors and a private conductor, means whereby the electrical condition of the terminal of the private conductor is determined by the line terminals over all said conductors, and automatically applied means made operative consequent upon the switch being selectively operated into connection with the terminals and one of said line conductors is not normally disposed with respect to other said conductors for causing the application 90 of the tone source for audibly indicating the condition. 95
59. In a telephone system, a connective switch, leading-in terminals for the switch, line terminals consisting of a pair of talking terminals and a private terminal, means for seizing the switch through the leading-in terminals and then automatically operating the switch from its normal position when seized into connection with the line terminals, 100 automatic means for thereafter restoring the switch to said normal position, line conductors leading from said line terminals consisting of a pair of normally closed circuit talking conductors and a private conductor, 105 means whereby the electrical condition of the private terminal is normally determined from the talking terminals over the talking conductors and the private conductor, and automatically applied means rendered effective consequent to the switch being operated into connection with said line terminals and one of said conductors is not normally disposed with respect to the other said conductors for disabling the restoring means. 110 115
60. In a telephone system, a connective switch, leading-in terminals for the switch, line terminals consisting of a pair of talking terminals and a private terminal, means for seizing the switch through the leading-in terminals and then automatically operating the switch from its normal position when seized into connection with the line terminals, automatic means for thereafter restoring 125 the switch to said normal position, line 130

- conductors leading from said line terminals consisting of a pair of normally closed circuit talking conductors and a private conductor, means whereby the electrical condition of the private terminal is normally determined from the line terminals over the talking conductors and the private conductor, and automatically applied means rendered effective consequent to the switch being operated into connection with said line terminals and the condition of the private terminal is not changed resultant to a changed condition of the talking terminals for disabling said restoring means.
61. In a telephone system, a connective switch, leading-in terminals for the switch, line terminals consisting of a pair of talking terminals and a private terminal, means for seizing the switch through the leading-in terminals and then automatically operating the switch from its normal position when seized into connection with the line terminals, automatic means for thereafter restoring the switch to said normal position, line conductors leading from said line terminals consisting of a pair of normally closed circuit talking conductors and a private conductor, relay means whereby the electrical condition of the private terminal is normally determined from the talking terminals over the talking conductors and the private conductor, and automatically applied means rendered effective consequent to the switch being operated into connection with said line terminals and one of said conductors in not normally disposed with respect to said relay means for disabling said restoring means.
62. In a telephone system, a connective switch, a signal device, a called line accessible from the switch, means for seizing the switch and then automatically operating the switch from normal position when seized into connection with the called line, means for causing the signal device to display consequent to the switch moving from its normal position to connect with the called line, and automatically applied means responsive only to the switch connecting with the called line for effacing the signal.
63. In a telephone system, a connective switch, a signal device, a line consisting of a closed circuit pair and a private conductor accessible from the switch, means for seizing the switch and then automatically operating the switch from normal position when seized into connection with said line conductors, a relay winding in series with said pair operative to change the condition of said private conductor, means for causing the signal device to display consequent to the switch moving from its normal position to connect with the called line, means responsive to said connection to operate the relay, and automatically applied means including the relay and the private conductor for effacing the signal whereby if any said conductor is not in normal condition the effacing of the signal will not occur.
64. In a telephone system, a connective switch, a signal device, a line consisting of a talking conductor and a private conductor accessible from the switch, means for seizing the switch and then automatically operating the switch from normal position when seized into connection with said line conductors, a relay winding energized over said talking conductor operative to change the condition of said private conductor, means for causing the signal device to display consequent to the switch moving from its normal position to connect with the called line, means responsive to said connection to operate the relay, and automatically applied means including the relay and the private conductor for effacing the signal whereby if said talking conductor or said private conductor is not in normal condition the effacing of the signal will not occur.
65. In a telephone system, a plurality of automatic switches, leading-in terminals for the respective switches, line terminals accessible from the respective switches consisting of a pair of talking terminals and a private terminal, means for seizing the respective switches through the corresponding leading-in terminals and then automatically operating only the seized switch from its normal position when seized into selective relation with its said line terminals to connect the corresponding leading-in terminals to the selected terminals, means determined by a specific condition of the private terminal when selected for barring connection of the leading-in terminals to the talking terminals of the switch, automatic means controlled over the leading-in terminals for restoring the corresponding switch from the selected terminals at will, line conductors leading from said line terminals of the switches the corresponding terminals of the respective switches being connected in multiple and consisting of a pair of talking conductors and a private conductor, a relay means normally controlled over a said talking conductor for effecting said specific condition of the private terminals, and automatically applied means independent of the operation of said means for restoring rendered effective consequent to the switch being operated into connection with its said line terminals if one of said conductors is not normally disposed with respect to the other said conductors for causing all said private terminals to permanently manifest said specific condition to bar any said switch from connecting its leading-in terminals with the said talking terminals.
66. In a telephone system, a plurality of automatic switches, leading-in terminals for

- the respective switches, line terminals accessible from the respective switches consisting of a pair of talking terminals and a private terminal, means for seizing the respective switches through the corresponding leading-in terminals and then automatically operating only the seized switch from its normal position when seized into selective relation with its said line terminals to connect the corresponding leading-in terminals to the selected terminals, means determined by a specific condition of the private terminal when selected for barring connection of the leading-in terminals to the talking terminals of the switch, automatic means controlled over the leading-in terminals for restoring the corresponding switch from the selected terminals at will, line conductors leading from said line terminals of the switches the corresponding terminals of the respective switches being connected in multiple and consisting of a pair of talking conductors and a private conductor, a relay means normally controlled over a said talking conductor for effecting said specific condition of the private terminals, automatically applied means rendered effective consequent to a switch being operated into connection with its said line terminals if one of said conductors is not normally disposed with respect to the other said conductors for disabling the restoring means and for causing all said private terminals to permanently manifest said specific condition to bar any switch from connecting its leading-in terminals with the said talking terminals, and means for unseizing the leading-in terminals of said operated switch without unbarring said barred condition to all said switches.
67. In a telephone system, a plurality of automatic switches, leading-in terminals for the respective switches, line terminals accessible from the respective switches consisting of a pair of talking terminals and a private terminal, means for seizing the respective switches through the corresponding leading-in terminals and then automatically operating only the seized switch from its normal position when seized into selective relation with its said line terminals to connect the corresponding leading-in terminals to the selected terminals, means determined by a specific condition of the private terminal when selected for barring connection of the leading-in terminals to the talking terminals of the switch, automatic means controlled over the leading-in terminals for restoring the corresponding switch from the selected terminals at will, line conductors leading from said line terminals of the switches the corresponding terminals of the respective switches being connected in multiple and consisting of a pair of talking conductors and a private conductor, a relay means normally controlled over a said talking conductor for effecting said specific condition of the private terminals, automatically applied means rendered effective consequent to a switch being operated into connection with its said line terminals if one of said conductors is not normally disposed with respect to the other said conductors for disabling the restoring means and for causing all said private terminals to permanently manifest said specific condition to bar any switch from connecting its leading-in terminals with the said talking terminals, and means for unseizing the leading-in terminals of said operated switch without unbarring said barred condition to all said switches.
68. In a telephone system, a connective switch, a tone source, line terminals including a talking terminal and a private terminal, leading-in terminals for the switch, means for seizing the switch through the leading-in terminals and then automatically operating the switch into connection with the line terminals, line conductors leading from said line terminals including a talking conductor and a private conductor, means whereby the electrical condition of the terminal of the private conductor is determined by said conductors, and automatically applied means made operative consequent upon the switch being selectively operated into connection with the terminals and one of said line conductors is not normally disposed with respect to other said conductor for causing the application of the tone source to audibly indicate the condition.
69. In a telephone system, a connective switch, leading-in terminals for the switch, line terminals including a talking terminal and a private terminal, means for seizing the switch through the leading-in terminals and then automatically operating the switch from its position when seized into connection with the line terminals, automatic means for thereafter restoring the switch from its said connection, line conductors leading from said line terminals including a talking conductor and a private conductor, means whereby the electrical condition of the private terminal is normally determined from the talking conductor and the private conductor, and automatically applied means rendered effective consequent to the switch being operated into connection with said line terminals and one of said conductors is not normally disposed with respect to the other said conductor for disabling said restoring means.
70. In a telephone system, a connective switch, leading-in terminals for the switch,

- line terminals including a talking terminal and a private terminal, means for seizing the switch through the leading-in terminals and then automatically operating the switch 5 from its position when seized into connection with the line terminals, automatic means for thereafter restoring the switch from its said connection, line conductors leading from said line terminals including a talking conductor 10 and a private conductor, means whereby the electrical condition of the private terminal is normally determined from the talking terminal over the talking conductor and the private conductor, and automatically applied means effective consequent to the 15 switch being operated into connection with said line terminals and the condition of the private terminal is not changed resultant to a changed condition of the talking terminal 20 for disabling said restoring means.
71. In a telephone system, a connective switch, leading-in terminals for the switch, line terminals including a talking terminal and a private terminal, means for seizing the switch through the leading-in terminals and then automatically operating the switch 25 from its position when seized into connection with the line terminals, automatic means for thereafter restoring the switch from its said connection, line conductors leading from 30 said line terminals including a talking conductor and a private conductor, relay means whereby the electrical condition of the private terminal is normally determined from 35 the talking terminal over the talking conductor and the private conductor, and automatically applied means rendered effective consequent to the switch being operated into connection with said line terminals and one 40 of said conductors is not normally disposed with respect to said relay means for disabling said restoring means.
72. In a telephone system, an automatic trunk selecting switch having movable contacts, trunk lines accessible to said switch and terminating in fixed contacts, means for 45 operating said switch to select and connect with an idle trunk, and a locking circuit for retaining said switch in operated position established automatically responsive to the 50 engagement of a non-talking movable contact of said switch with a fixed contact associated with the selected trunk.
73. In a telephone system, an automatic trunk selecting switch and trunk lines accessible thereto, means for operating said switch to select and connect with an idle trunk, and a locking circuit for retaining said switch in operated position established 55 responsive to the completion of the connection with the selected trunk and independent of the continuity of either talking conductor of said trunk.
74. In a telephone system, a trunk hunting switch comprising a relay, a trunk accessible to said switch, means controlled by a calling subscriber through the medium of 65 said relay for operating said switch to seize said trunk, and means independent of the calling subscriber for locking said switch on said trunk responsive to the seizure thereof. 70
75. In a telephone system, a trunk hunting switch comprising a relay, a trunk accessible to said switch, means controlled by a calling subscriber through the medium of 75 said relay for operating said switch to seize said trunk, means independent of the calling subscriber for locking said switch on said trunk responsive to the seizure thereof, and means operated automatically only when 80 said trunk is in working condition to place said switch under control of the calling subscriber.
76. In a telephone system, a trunk line, an automatic switch, subscriber controlled 85 means for operating said switch to extend a connection to said trunk line, subscriber controlled releasing means for said switch, means for removing said releasing means from the control of the subscriber when the 90 trunk line is connected with until it is determined that the trunk line is in operative condition, and means for indicating the non-releasable connection to an attendant in case the trunk line proves to be in inoperative 95 condition.
77. In an automatic telephone system, a repeater, a trunk line extending from said repeater to a distant exchange, means for completing a connection over said trunk line, said means including an automatic switch for connecting with said repeater, means for releasing the connection, a relay in said repeater connected in bridge of said trunk line when the connection is released, 100 and circuit arrangements whereby the release of said switch is made dependent on the energization of said relay by current flow over the trunk line. 105
78. In a telephone system, a trunk line comprising two inductively connected sections, means including an automatic switch for connecting with the first section of said trunk line, a repeater at the junction of said sections, a relay in said repeater controlled 110 over the first section for closing a holding circuit for said switch and for opening said circuit to release said switch, a branch holding circuit for preventing the release of said switch, and a relay energized over the second section of said trunk line for opening said branch circuit. 115
- In witness whereof, I hereunto subscribe my name this 21st day of October A. D., 1920.

HERBERT M. FRIENDLY.
